CLAIM

The ornamental design for an automobile telephone set, as shown and described.

DESCRIPTION

FIG. 1 is a right side elevational view of an automobile telephone set showing my new design in cradled relationship, the side opposite being a mirror image; FIGS. 2 and 3 are respectively top and bottom plan views thereof;

FIGS. 4 and 5 are respectively front and rear elevational views thereof; and

FIG. 6 is a bracket associated top plan view of the base component of the automobile telephone set, and a bottom plan view of the handset component of the telephone set.

fig. 1.

fig. 2.

FIG. 3.

FIG. 5.

FIG. 4.

Fig. 6.
